(57) **CLAIM**

The ornamental design for a bracelet, as shown and described.

DESCRIPTION

FIG. 1 is a perspective view of a bracelet showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is another perspective view thereof, showing the bracelet of FIG. 1 in a stacked configuration.

The broken lines in the drawings illustrate portions of the bracelet that form no part of the claimed design. The stacked bracelets shown in broken lines in FIG. 8 represent environmental subject matter only and form no part of the claimed design.
